(57) **CLAIM**

I claim the ornamental design for a facial skin observation device, as shown and described.

DESCRIPTION

FIG. 1 is a front elevational view of a facial skin observation device, showing my new design;

FIG. 2 is a rear elevational view thereof;

FIG. 3 is a right side elevational view thereof, the left side being a mirror image;

FIG. 4 is a top plan view thereof;

FIG. 5 is a bottom plan view thereof; and,

FIG. 6 is a perspective view thereof, shown at a reduced scale.
